UNITED STATES PATENT OFFICE.

BYRON S. BLAKE AND EDWIN A. LONGSHORE, OF DES MOINES, IOWA; SAID LONGSHORE ASSIGNOR TO SAID BLAKE.

MIXING-MACHINE.

No. 852,406.

Specification of Letters Patent.

Patented April 30, 1907.

Application filed June 4, 1906. Serial No. 320,193.

To all whom it may concern:

Be it known that we, BYRON S. BLAKE and EDWIN A. LONGSHORE, citizens of the United States, residing at Des Moines, in the county 5 of Polk and State of Iowa, have invented certain new and useful Improvements in Mixing-Machines; and we do declare the following to be a full, clear, and exact description of the invention, such as will enable others 10 skilled in the art to which it appertains to make and use the same.

This invention relates to improvements in mixing machines, and consists in the novel construction, combination and arrangement 15 of parts hereinafter described and claimed.

The object of the invention is to provide a simple, practical and efficient machine of this character in which either dry or liquid substances of any description may be quickly 20 and thoroughly mixed.

The above and other objects which will appear as the nature of the invention is better understood, are accomplished by the construction illustrated in the accompanying 25 drawings, in which:—

Figure 1 is a side elevation of the improved mixing machine, and Fig. 2 is a vertical sectional view through the same.

Referring to the drawings by numeral, 1 30 denotes my improved mixing machine, which has a revolving hollow drum or container 2 in the form of two cone frustums united at their bases and mounted to revolve on a diagonal axis. By making the drum in this 35 shape and mounting it for rotation on its diagonal axis, it will impart an alternate falling and lifting motion to its contents, which tends to throw the material in the center toward each end of the machine and from each 40 end of the machine to its center, at the same time that the material is being overturned, hence causing the material to be thoroughly mixed. As shown, the two cone frustums 3, 4 are united at their bases 5, so that the 45 drum is closed and hollow. The journals for the drum are preferably in the form of castings 6 and 7, which have cylindrical portions 7 to rotate in suitable bearings in uprights 8 or other supports, and which have attaching 50 flanges 9 shaped to fit the cone frustums on which they are bolted or otherwise secured. The journal 7 of the casting 6 has secured upon its outer end, a gear wheel 10, which meshes with a pinion 11 secured upon a short

shaft 12, which is journaled in one of the uprights 8 and which has upon its outer end a crank handle 13. The journal 7 of the casting 5 is bored to receive a water or other liquid supply pipe 14. The latter has its inner end extending into the drum and bent at 60 right angles, as shown at 15. By constructing the discharge end of this liquid supply pipe in this manner, it will be seen that there will be no danger of the contents of the drum getting in the same and choking it up when 65 the drum is revolved. Water or other liquid may be supplied to the outer end of the pipe 14 in any desired manner, and any suitable means may be provided for controlling its passage through said pipe. The materials to 70 be mixed in the drum are inserted therein through an opening formed in one of its cone frustums and closed by a cover 17 which is preferably detachably secured in said opening, as shown at 18.

The construction, operation and advantages of the invention will be readily understood from the foregoing description taken in connection with the accompanying drawings. By making the drum 2 in the form of 80 a double cone frustum and mounting it for rotation upon a diagonal axis, as shown, its contents will be given a peculiar motion which will cause the substances to be quickly and thoroughly mixed.

While the present embodiment of the invention is in the form of a device especially adapted for mixing cement and the like, it will be understood that it may be adapted for other uses. It will also be understood 90 that it may be made in any size and of any material, and that it may be operated by hand or power.

Various other changes in the form, proportion and minor details of construction may 95 be resorted to without departing from the principle or sacrificing any of the advantages of the invention, as defined by the appended claim.

Having thus described our invention, what 100 we claim as new and desire to secure by Letters-Patent is:—

The herein-described mixing machine comprising supports, a hollow drum formed of two conic frustums, united at their bases, 105 said drum having an opening in one side and a closure for said opening, journals on said drum for rotation in bearings on said sup-

ports, said journals being in longitudinal alinement on a diagonal axis of said drum intersecting corners thereof and each provided with angularly-disposed base flanges overlapping, reinforcing and secured respectively to one end and one side of the drum, one of said journals being solid and the other being hollow, a liquid supply pipe extending through said hollow journal and an opening 5 in the corner of the drum to which said journal is secured, a gear on the solid journal on the outer side of one of said supports, a crank 10

shaft journaled in the said support and a pinion on the said crank shaft meshing with the said gear.

In testimony whereof we have hereunto set our hand in presence of two subscribing witnesses.

BYRON S. BLAKE.
EDWIN A. LONGSHORE.
